CLAIM

The ornamental design for a base for phone and tablet holder
as shown and described.

DESCRIPTION

FIG. 1 is a perspective view of a base for phone and tablet holder showing my present design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view thereof in an alternate position of use;

FIG. 9 is a schematic view of the base, shown in an environment of use; and,

FIG. 10 is a schematic view of the base shown in an environment of use.

The broken lines shown in FIG. 9 and FIG. 10 depict environmental subject matter and form no part of the claimed design.

1 Claim, 10 Drawing Sheets
